PHILIP DIEHL, OF ELIZABETH, NEW JERSEY, ASSIGNOR TO THE SINGER
MANUFACTURING COMPANY OF NEW JERSEY.

FEEDING MECHANISM FOR SEWING-MACHINES

SPECIFICATION forming part of Letters Patent No. 440,622, dated November 18, 1890.

Application filed July 1, 1886. Serial No. 206,811. (No model.)

To all whom it may concern:

Be it known that I, PHILIP DIEHL, of Elizabeth, county of Union, and State of New Jersey, have invented an Improvement in Feeding Mechanism for Sewing-Machines, of which the following description, in connection with the accompanying drawings, is a specification, like letters on the drawings representing like parts.

10 This invention has for its object the production of a novel mechanism for actuating the feeding device or bar, the same being moved positively from the main shaft in the overhanging arm of the machine, the construction of the mechanism enabling the 15 length of the feed to be readily adjusted.

In this my invention the feed-bar to be reciprocated is shown as jointed at one end to an arm of a rocking shaft parallel to the main 20 rotating shaft, the latter being provided with a cam or eccentric, which is embraced by two arms of a forked lever provided with a guiding slot or way, with which co-operates a block pivoted upon a link, the lower end of which 25 is jointed directly to an arm of the same rocking shaft to which is jointed the said feed-bar to be reciprocated, the said link having combined with it means, as hereinafter described and claimed, whereby the position 30 of the block attached to it may be moved toward or from the fulcrum of the said forked lever and in or with relation to the said slot or way. The greater the distance of the said block from the said fulcrum the greater the 35 longitudinal movement of the said link and the greater the length of the stroke or reciprocation of the feed-bar actuated by the said rocking shaft.

Figure 1 in side elevation represents a sufficient portion of a sewing-machine to enable 40 my invention to be understood; Fig. 2, a right-hand elevation thereof to the left of the dotted line xx , Fig. 1, the link and forked lever being shown as dotted in behind the frame-work; and Figs. 3 and 4, details to be referred to.

The bed-plate A, upright arm A', and overhanging arm A² constitute part of the frame-work.

50 The feed-bar a to be reciprocated has at

one end, as herein shown, a toothed block a', which enters a slot or opening in the plate A. The rear end of this feed-bar is jointed to one or more arms a² of a rocking shaft a³, sustained by point-screws a⁴ a⁵. This rocking shaft has an arm a⁵, to which is jointed the lower end of a link b, provided at its upper end with a swivel block or slide b', which co-operates with a slot or guideway b⁵ of a forked or bifurcated lever b³, having its fulcrum at b⁴, the said slot or guideway b⁵ in the said lever being made across the same in a diagonal direction, the fulcrum of the said lever being near one end of the said slot. The forked end of the lever b³ embraces a 55 cam or eccentric b⁶ on the rotating shaft d, having proper bearings in the frame-work and rotated in any usual manner. The link b is connected to the screw e by a coupling-link e'. The threads of the screw e, preferably left-handed, are surrounded and engaged by a thumb-nut e², threaded externally, preferably right-handed, and of coarser pitch than the threads of the screw e. The nut e² is 60 screwed into the frame-work, and when turned 65 in one direction or the other moves longitudinally with it the screw e at a speed equal to the difference in the pitch of the threads of the said screws. The turning of the nut causes the link b to be moved so as to place 70 the swivel block or stud b' closer to or farther from the fulcrum of the lever b³ in the slot or guideway b⁵, so that as the said lever is rocked by the cam or eccentric the link b is moved in the direction of its length for a 75 greater or less distance, the farther the block b' from the fulcrum b⁴ the greater the stroke of the link b and the greater the extent to which the rocking shaft a³ is turned and the greater the stroke or reciprocation of the feed-bar a, and vice versa.

I claim—

In a sewing-machine, the combination, with the rotating shaft d, provided with a cam or eccentric, of the forked lever b³, embracing the said cam or eccentric and having the slot b⁵, the said lever being pivoted near one end of the said slot, the feed-bar a, the rocking shaft a³, with which the said feed-bar is connected, the link b, jointed to an arm of the 95 100

said shaft a^3 , the block or stud carried by the said link and entering the said slot b^5 , the link e' , jointed to the said link b , the screw e , provided with ears to which the said link e' is pivoted, and the adjusting-nut e^2 , tapped-in 5 the frame-work and threaded internally to receive the shank of the said screw e' , the external threads of the said nut being of a coarser pitch than the threads of the said

screw, whereby a differential adjustment is to secured, substantially as set forth.

In testimony whereof I have signed my name to this specification in the presence of two subscribing witnesses.

PHILIP DIEHL.
